UNITED STATES PATENT OFFICE.

JOHN F. WHITE, OF PITTSBURG, PENNSYLVANIA.

MACHINE FOR PERFORATING SHEET-MUSIC.

981,341.

Specification of Letters Patent. Patented Jan. 10, 1911.

Application filed August 5, 1910. Serial No. 575,615.

To all whom it may concern:

Be it known that I, JOHN F. WHITE, a citizen of the United States of America, residing at N. S. Pittsburg, in the county of 5 Allegheny and State of Pennsylvania, have invented certain new and useful Improvements in Machines for Perforating Sheet-Music, of which the following is a specification, reference being had therein to the accompanying drawing.

This invention relates to a machine for perforating music-sheets, and the objects of the invention are to provide positive and reliable means for expeditiously and economically 15 perforating sheets of paper or other suitable material for use in musical instruments commonly styled "automatic pianos," "piano players," and the like, and to accomplish the above object by a mechanical construction 20 that is simple, durable, easy to operate, and efficient for the purposes for which it is intended.

Further objects of the invention are to utilize electrical devices for actuating punches, 25 and to arrange and assemble the electrical devices and their pertinent parts in such a manner that they will be accessible and occupy a comparatively small space.

These and such other objects as may hereinafter appear are attained by the novel construction, combination, and arrangement 30 of parts to be hereinafter specifically described and then claimed.

Reference will now be had to the drawings, wherein:

Figure 1 is a front elevation of the perforating machine. Fig. 2 is a side elevation of the same. Fig. 3 is an enlarged cross sectional view of the upper part of the machine, 40 showing the electrical devices. Fig. 4 is an enlarged cross sectional view of a portion of the lower part of the machine, showing the punches. Fig. 5 is a perspective view of a detached electrical device 45 adapted to form part of the machine. Fig. 6 is an enlarged cross sectional view of one of the electrical devices, partly in elevation. Fig. 7 is a plan of a portion of a perforated sheet.

50 A machine in accordance with my invention comprises two frames 1 and 2, the frame

1 being of a less height than the frame 2. These frames have the upper ends thereof provided with angular extensions 3 and 4 respectively, said extensions being arranged in 55 parallelism and the extension 3 connected to the base 5 of the frame 1 by a web 6, while the frame 2 is reinforced relatively to the base 7 of said frame by a web 8.

Journaled in the upper ends of the angular extensions 3 and 4 is a longitudinal shaft 9 and mounted upon one end of said shaft is a belt or sprocket wheel 10, whereby the shaft 9 can be driven by a suitable source of power. Mounted upon the opposite end of 60 the shaft is a large beveled gear wheel 11 meshing with a small gear wheel 12 mounted upon an angularly disposed shaft 13, journaled in a bearing 14, carried by the angular extension 3 and in a bracket 15, carried by the outer side of the frame 1 to one side of the web 6. The lower end of the shaft 13 is provided with a beveled pinion 16 meshing with a large beveled gear wheel 17 mounted upon a shaft 18 journaled in the 65 frame 1. The hub 19 of the large gear wheel 17 is provided with a radially disposed pin 20 adapted to actuate a star or toothed wheel 21 mounted upon the end of a shaft 22 journaled in the frames 1 and 2. 70 The shaft 22 adjacent to the toothed wheel 21 is provided with a ratchet wheel 23 and engaging said wheel is a spring-pressed pawl 24 carried by the outer side of the frame 1, said pawl preventing a rearward rotation of 75 the ratchet wheel. The pawl is normally held in engagement with the ratchet wheel by a flat spring 25 secured to the outer side of the frame 1. The shaft 22 extends through the frame 2 and is provided with a 80 small gear wheel 25 meshing with another gear wheel 26 mounted upon the end of a shaft 27, journaled in the frames 1 and 2 above the shaft 22. Mounted upon the shafts 22 and 27 are feed rollers 28 and 29 85 respectively.

Connecting the frames 1 and 2 adjacent to the feed rollers 28 and 29 is a die plate 30 and a guide plate 31, the guide plate being located directly above the die plate 30. The 90 die plate 30 is provided with openings 32 and dies 33, while the guide plate 31 is pre- 100

vided with openings 34 adapted to vertically align with the openings 32 and with the openings of the dies 33, the openings 34 guiding punches 35 employed for perforating sheets of paper as it is carried between the plates 30 and 31 by the feed rollers 28 and 29.

The confronting sides of the angular extensions 3 and 4 are connected by a longitudinal platform 36 and extending upwardly through the ends of said platform upon the inner sides of the extensions 3 and 4 are guides 37 for a reciprocating frame or member, comprising a head 38, side bars 39 and end plates 40, these plates being provided in their outer faces with vertical grooves 41 to receive the guides 37 of the angular extensions 3 and 4. The head 38 of the reciprocating frame adjacent to each end thereof is provided with apertured lugs 42 and pivotally connected to said lugs by pins 43 are the depending arms 44 of eccentric rings 45 movably mounted upon eccentrics 46 secured to the shaft 9.

Upon the platform 36 are mounted a plurality of electrical devices, the devices being arranged in two rows corresponding in number to the keys of a piano. Each device comprises an electro-magnet 47 mounted upon a tiltable support 48, said support having depending oppositely disposed apertured lugs 49 pivotally connected by a pin 50 to apertured bearings 51, carried by the platform 36. Slidably mounted in the base 52 of the electro-magnet is a detent 53 having the forward end thereof bent upwardly, as at 54. Encircling the detent 53 between the base 52 and the forward end thereof is a coiled compression spring 55 adapted to normally retain the forward end of the detent in engagement with a pivoted armature 56 having the upper end thereof pivotally connected by a pin 57 to a forwardly extending lug 58, carried by the upper edge 45 of the electro-magnet 47. An outward movement of the pivoted armature 56 is limited by a stop 59, carried by the edge of the tiltable support 48. The tiltable support 48 is normally retained in a horizontal position by a coiled spring 60 arranged between one end of said support and the platform 36, and the tilting of said support is limited by an upright 61, carried by the platform 36, but in the majority of instances it is not necessary to use these uprights. The forward end of the support 48 is provided with depending apertured lugs 62 and pivotally connected to these lugs by a pin 63 is the upper end of a connecting rod 64, said rod 60 extending through an opening 65 provided therefor in the platform 36. The lower end of the connecting rod 64 is connected by a universal coupling or link 66 to the arm 67

of a bell crank lever 68, said lever being pivotally mounted upon the side of a plate 69 connecting the angular extensions 3 and 4, this plate being arranged at the upper ends of the frames 1 and 2. The bell crank lever 68 is pivotally supported by a pin 70 extending through the plate 69, said pin also serving to support a similar bell crank lever upon the opposite side of the plate. The bell crank lever is connected by a universal coupling or link 71 to a connecting rod 72 extending downwardly between the frames 1 and 2, and having the lower ends thereof pivotally connected by a pin 73 to an arm 74 fulcrumed upon a rod 75 connecting the frames 1 and 2 above the guide plate 31. The opposite end of the arm 74 is loosely mounted in the upper bifurcated end 76 of one of the punches 35.

As heretofore stated, the number of electrical devices corresponds to the keys of a piano and they are arranged in two rows at an inclination to the guide plate 31 whereby the punches 35 can be compactly arranged to punch a narrow strip of paper. The punches are arranged in a single row with some of the punches of a greater length than the others, whereby one of the rods 75 can be located in a plane above the other.

The electro-magnets constituting the electrical devices can be energized from a suitable source of energy, either in connection with electrically connected piano keys or a master sheet, and when the electro-magnets are energized, the pivoted armatures 56 thereof immediately move the detents 53 into the path of the side bars 39 of the reciprocating frame. As the frame is reciprocated through the medium of the shaft 9 and the eccentrics 46, the side bars 39 will impinge those detents that are extended through the medium of the electro-magnets 47, and the supports 48 of the energized electro-magnets will be tilted to pull upwardly upon the connecting rod 64, rock the bell crank lever 68, raise the connecting rod 72, rock the fulcrumed arms 74 and lower the punches 35 with sufficient force to perforate the sheet of paper passing between the plates 30 and 31.

In Fig. 2 of the drawings I have illustrated in dotted lines a sheet of paper and in Fig. 7 have shown an enlarged portion of the same, the sheet being designated 77. As the sheet is carried between the plates 30 and 31 by the feed rollers 28 and 29, which are moved through the medium of the mechanism previously described, the punches 35 descend and either provide the paper with rows of single perforations 78 or communicating perforations 79 corresponding to slots. A single perforation is accomplished by the reciprocating bar im-

pinging the detent once, the electro-magnet controlling the movement of the detent simply being energized for that period of time required for the side bar of the reciprocating frame to strike the detent. To produce communicating perforations the electro-magnet is energized to hold the detent thereof in an extended position until the side bar 39 of the reciprocating frame 5 has engaged the detent a sufficient number of times to produce a slot. For instance the slot designated 79 is equivalent to six single perforations. While the reciprocating frame 10 is being reciprocated, the sheet of paper is 15 gradually moved between the plates 30 and 31, consequently rows of perforations or slots will be produced during the operation of the machine. When an electro-magnet is deenergized the coiled spring 55 surrounding 20 the forward end of the detent 53 immediately restores the detent to its normal position, also the pivoted armatures 56, and the spring 60 beneath the rear end of the support 48 restores said support to a horizontal 25 position. The shafts 18 and 27 can be extended and provided with feed rollers 80 for moving a master sheet, which will control in connection with the suitable source of electrical energy the energizing of the 30 electro-magnets 47. To assist in restoring the fulcrumed arms 74, the punches 35 and the connecting rod 72 to their normal position, the frames 1 and 2 are connected by transverse bars 81 and secured to these bars 35 are flat springs 82 adapted to engage the rear ends of the arms 74, these springs being placed under tension when the punches are placed in operation, and the tension of the springs restoring the punches to their 40 normal position when the bar reciprocates or makes an upward stroke.

From the foregoing it will be observed that I have devised a compact machine embodying horizontally arranged punches, angularly disposed tilttable electro-magnet supports normally retained in an inactive position and adapted to actuate said punches, detents carried by said supports and adapted to be shifted by the energizing of said electro-magnets to place said supports in an active position, a reciprocating frame for tilting said supports, and means for simultaneously operating said frame and moving a sheet of paper beneath said punches. It is 45 by this combination of elements that a sheet of paper is easily, quickly and accurately punched.

What I claim is:—

1. In a perforating machine, movably 50 mounted punch actuating electro-magnets normally in inactive position and disposed at an angle to the punches to be actuated thereby, and a reciprocating frame for mov-

ing said electro-magnets to actuate the punches. 65

2. In a perforating machine, movably mounted punch actuating electro-magnets, a reciprocating frame for moving said magnets to actuate said punches, and means adapted to move a sheet of paper beneath the punches. 70

3. In a perforating machine, punches, movably mounted electro-magnets disposed at an angle to said punches and adapted to actuate said punches, and a reciprocating frame adapted to move said electro-magnets. 75

4. In a perforating machine, punches, movably mounted electro-magnets disposed at an angle to said punches and adapted to actuate said punches, a reciprocating frame 80 adapted to move said electro-magnets, and means for simultaneously moving a sheet of paper beneath said punches and to operate said reciprocating frame.

5. In a perforating machine, punches, 85 movably mounted electro-magnets adapted to actuate said punches, detents movable with said electro-magnets and adapted to be extended by the energizing of said electro-magnets, and a reciprocating frame adapted 90 to impinge said detents and move said electro-magnets to actuate said punches.

6. In a perforating machine, punches, movably mounted electro-magnets adapted to actuate said punches, detents movable 95 with said electro-magnets and adapted to be extended by the energizing of said electro-magnets, a reciprocating frame adapted to impinge said detents and move said electro-magnets to actuate said punches, and means 100 for reciprocating said frame.

7. In a perforating machine, punches, movably mounted electro-magnets adapted to actuate said punches, detents movable with said electro-magnets and adapted to be 105 extended by the energizing of said electro-magnets, a reciprocating frame adapted to impinge said detents and move said electro-magnets to actuate said punches, means for reciprocating said frame, and means actuated by the first mentioned means and adapted 110 to move a sheet of paper beneath said punches.

8. A perforating machine comprising frames, punches located between said frames, means adapted to move a sheet of paper beneath said punches, angularly disposed extensions carried by the upper ends of said frames, and a plurality of tilttable electrical devices arranged between said extensions and 115 when tilted adapted to actuate said punches.

9. A perforating machine comprising frames, punches located between said frames, means adapted to move a sheet of paper beneath said punches, angularly disposed extensions carried by the upper ends of said 120

- frames, a plurality of tilttable electrical devices arranged between said extensions and when tilted adapted to actuate said punches, and a reciprocating frame arranged between 5 said extensions and adapted to tilt said electrical devices.
10. A perforating machine comprising frames, a plurality of punches arranged between said frames, means adapted to move a sheet of paper beneath said punches, angularly disposed extensions carried by the upper ends of said frames, tilttable electro-magnet supports arranged between said extensions and adapted to actuate said punches, 15 detents movably mounted upon said supports and adapted to be moved by the energizing of said electro-magnets, and means including a reciprocating frame for engaging said detents and tilting said supports.
20. 11. A perforating machine embodying horizontally arranged punches, angularly disposed tilttable electro-magnet supports adapted when tilted to actuate said punches, and means arranged above said supports and 25 adapted to tilt the same.
12. A perforating machine embodying horizontally arranged punches, angularly disposed, tilttable electro-magnet supports adapted when tilted to actuate said punches, 30 means arranged above said supports and adapted to tilt the same, and means adapted to move a sheet of paper beneath said punches.
13. A perforating machine embodying 35 frames, horizontally arranged punches supported between said frames, a sheet of paper adapted to be moved beneath said punches, angularly disposed tilttable electro-magnet supports supported by the upper ends of 40 said frames and adapted to actuate said punches, a reciprocating frame adapted to tilt said supports, and means adapted to simultaneously reciprocate said frame and move said sheet of paper beneath said 45 punches.
14. A perforating machine embodying frames, horizontally arranged punches supported between said frames, a sheet of paper adapted to be moved beneath said punches, 50 angularly disposed tilttable electro-magnet supports supported by the upper ends of said frames and adapted to actuate said punches, a reciprocating frame adapted to tilt said supports, means adapted to simultaneously reciprocate said frame and move 55 said sheet of paper beneath said punches, said means including a driven shaft, eccentricities and feed rollers revolved through the medium of said driven shaft.
60. 15. In a perforating machine, punches, tilttable electro-magnet supports adapted to actuate said punches and normally in an inactive position, detents carried by said sup-

ports and adapted to be shifted by the energizing of the electro-magnets of said supports to place said supports in an active position, and means adapted to impinge said detents and cause said supports to tilt and 65 actuate said punches.

16. In a perforating machine, a punch reciprocating mechanism, operating means therefor including a shiftable detent, an electrical device for shifting the detent, and means engaging said detent when shifted for actuating said operating means, causing 75 thereby the operation of said mechanism.

17. In a perforating machine, a punch reciprocating mechanism, operating means therefor including a shiftable detent, an electrical device for shifting the detent, and 80 a reciprocatory means engaging said detent when shifted for actuating said operating means, causing thereby the operation of said mechanism.

18. In a perforating machine, a plurality 85 of punch reciprocating mechanisms, independent operating means for each of said mechanisms and including a shiftable detent, an independent electrical device for shifting each of the detents, and means engaging 90 a detent when shifted for actuating the operating means of which the shifted detent is an element, causing thereby the operation of a punch reciprocating mechanism.

95 19. In a perforating machine, a plurality of punch reciprocating mechanisms, independent operating means for each of said mechanisms and including a shiftable detent, an independent electrical device for 100 shifting each of the detents, and a reciprocatory means engaging a detent when shifted for actuating the operating means of which the shifted detent is an element, causing thereby the operation of a punch reciprocating mechanism.

105 20. In a perforating machine, a punch reciprocating mechanism, a tilttable operating means therefor including a shiftable detent, an electrical device for shifting the detent, 110 and means engaging said detent when shifted for tilting said operating means, causing thereby the operation of said mechanism.

115 21. In a perforating machine, a punch reciprocating mechanism, a tilttable operating means therefor including a shiftable detent, an electrical device for shifting the detent, and a reciprocatory means engaging said detent when shifted for tilting said operating means, causing thereby the operation of 120 said mechanism.

125 22. In a perforating machine, a plurality of punch reciprocating mechanisms, a tilttable operating means for each of said mechanisms and including a shiftable detent, an

independent device for shifting each of the detents, and means engaging a detent when shifted for tilting the operating means of which the shifted detent is an element, causing thereby the operation of a punch reciprocating mechanism.

23. In a perforating machine, a plurality of punch reciprocating mechanisms, a tiltable operating means for each of said mechanisms and including a shiftable detent, an independent device for shifting each of the detents, and a reciprocating means common

to all of the detents and engaging a detent when shifted for tilting the operating means of which the shifted detent is an element, 15 causing thereby the operation of a punch reciprocating mechanism.

In testimony whereof I affix my signature in the presence of two witnesses.

JOHN F. WHITE.
